SHIRT HOLD-DOWN ATTACHMENT FOR SUSPENDERS

Edwin S. Mix, Rochester, N. Y., assignor to Hickok Manufacturing Company, Inc., Rochester, N. Y., a corporation of New York

Application October 14, 1933, Serial No. 693,662

1 Claim. (Cl. 241—12)

The invention relates to a shirt hold-down attachment for suspenders.

The object of the present invention is to provide an ornamental, attractive and inconspicuous shirt hold-down attachment for suspenders adapted for gripping a shirt in two places and of exerting downward and lateral pull on the same and of thereby maintaining the bosom of the shirt in a smooth, flat and unwrinkled condition.

10 A further object of the invention is to provide a shirt hold-down attachment adapted to be manufactured as a unit in mass production and capable of being readily attached to suspenders without necessitating any addition to the suspenders or alteration in the construction thereof.

With these and other objects in view, the invention consists in the construction and novel combination and arrangement of parts hereinafter fully described, illustrated in the accompanying drawings, and set forth in the claim hereto appended, it being understood that various changes in the form, proportion, and minor details of construction, within the scope of the claim, may be resorted to without departing from the spirit of the invention or sacrificing any of the advantages thereof.

In the drawings:—

Figure 1 is a front elevation of a pair of suspenders provided with a shirt hold-down attachment constructed in accordance with one form of the present invention, the loop of one of the shoulder straps being partially broken away to show the inner end of the adjacent elastic member.

Fig. 2 is a detail longitudinal sectional view on the line 2—2 of Fig. 1.

Fig. 3 is a detail perspective view of one of the metal connecting links.

Fig. 3^a is a detail view partly in plan and partly in elevation of one of the metal tab or coupling connections for the inner ends of the elastic shirt engaging members.

Fig. 4 is a detached detail view of one of the elastic shirt engaging members and the connecting link which connects the shoulder straps and suspender ends.

Fig. 4^a is a cross sectional view on the line 4^a—4^a of Fig. 4.

Fig. 5 is a sectional view on the line 5—5 of Fig. 4.

Fig. 6 is a fragmentary front elevation of one side of a pair of suspenders illustrating another embodiment of the invention.

Fig. 7 is a sectional view on the line 7—7 of Fig. 6.

Fig. 8 is a detached detail plan view of one of

the elastic shirt engaging members and the connecting plate between the shoulder straps and suspender ends, illustrating more clearly the attachment illustrated in Figs. 6 and 7.

Fig. 9 is another modified form of connection between the elastic shirt holding members and a suspender connecting link.

Fig. 10 illustrates another modified form of connection between the elastic shirt holding members and a suspender connecting link.

In the accompanying drawings, and referring more particularly to Figs. 1 to 5, inclusive, the reference character 1 indicates a pair of suspenders having shoulder straps of elastic or non-elastic material provided at their front ends with loops 2 which are adjustable by means of buckles 3 to vary the lengths of the shoulder straps.

Suspender ends 4 of any suitable character are connected with the loops 2 of the shoulder straps by means of links 5 which consist, in this instance, of a metal plate provided with a slot 6 and a depending guide 7, the loops 2 of the shoulder straps being linked into the slots 6 of the respective connecting links 5 in the ordinary manner.

The shirt hold-down attachment, which may be applied to various suspenders, as illustrated in Figs. 1 to 5 inclusive, comprises a pair of elastic members 8, each consisting of a relatively short narrow strip of elastic webbing or other suitable material having their inner ends arranged between the front and rear sides of the loops 2 of the shoulder straps and extending upwardly from the connecting links 5 and provided at their upper or outer ends with ornamental clips 9 adapted to clip or grip the fabric of a shirt at opposite sides of the bosom whereby these elastic members of the hold-down attachment will exert a downward and lateral pull on the front of the shirt in two directions and will hold the bosom in a smooth, flat and unwrinkled condition.

The inner ends of the elastic members are connected with the links 5, in this instance, by metal or other tabs 10. These metal tabs 10 may each be formed from a flat piece of thin sheet metal, as shown in Fig. 3^a, and each consists of a body portion 11 having a tapered outer end 12 bent to terminate in a hook 13 adapted to loosely embrace the inner end of the respective link 5 through the slot 6 of the respective link 5 and be maintained against lateral sliding movement on the link by reason of the ends of the slot 6 or by reason of said hook engaging in any one of

the several recesses 14 in each link 5 leading to the respective slot 6 and by virtue of which the tabs are concealed between the loop 2 of the respective suspender straps 1. The flat material of each body portion 11 of which the tab 10 is formed, has bendable fingers 15 and 16. The inner end of the respective elastic member 8 is folded back upon itself and the pair of fingers 15 is bent over on the inner end of the respective elastic member 8 between the same and the folded over portion, said pair of fingers thereby lying between the folds of the elastic material 8 and at the bight portion of the fold. The pair of fingers 16 of the respective inner tab is bent over the two-ply thickness of material incident to said folded inner end, whereby to securely fasten the inner ends of the elastic members 8 to the respective inner tabs by bending said fingers 15 and 16 over on to the inner end of the respective elastic member as just described. The inner end of each elastic member 8 may be secured to other forms of tabs and in different ways as is evidenced by the modifications of the invention disclosed in the specification and drawings.

Tabs are secured to the outer ends of the relatively short elastic members 8 and these tabs may consist each of a body portion 17 including sets of bendable fingers 18 and 19 adapted to be bent over the folded outer end of the respective elastic member so as to clamp the outer end of the latter between the fingers 18 and 19 in the same manner as the fingers 15 and 16 connect the inner ends of the elastic members 8. The outer end of each of these second mentioned tabs has a tapered socket 20 in which the inner end of the side element 21 of the respective clip 9 is clamped.

The clips 9 which are preferably of an ornamental character, are each preferably composed of two sides 21 and 22 of unequal length and a connecting bend 23 located at the outer end of the clip. The longer side of the clip has its inner end tightly clamped in the outer tapering end 45 or socket 20 of the respective tab. This clamping of the ends of the elastic members 8 in the respective inner and outer tabs may be effected by a pressing action or otherwise and the clips 9 may be likewise secured in their respective sockets at the outer tabs. The shorter side 22 of each clip has its terminal portion 24 curved laterally to form a flaring entrance to a narrow space between the adjacent longitudinal edges of the sides 21 and 22 of the clip. A portion of the shirt is securely gripped between the side edges 55 25 and 26 which are oppositely beveled to form effective gripping portions.

When the elastic members are engaged with a shirt at opposite sides of the front portion thereof, they converge upwardly and exert a downward and a lateral pull which is sufficient to maintain the bosom of the shirt in a smooth, flat, unwrinkled condition.

65

70

In the modification shown in Figs. 6 to 8 inclusive, the inner ends of the elastic members 8' are secured to the connecting plate 27 by means of tabs 28 of leather or other suitable material doubled to form inner and outer sides and a connecting lower portion, the inner ends of the elastic members 8' being secured between the sides of the tab 28 by lines of stitching 29 or other suitable means.

These tabs 28 form terminal loop portions which are linked into an upper opening 30 in the respective connecting link 27 and these said tabs in this modified form are arranged between the inner the outer sides of the loops 2' of the shoulder straps and are concealed within the loops 2' of the straps 1'. In this modified form the suspender ends 31 are secured in any suitable manner in the lower slot 32 of the respective link 27. The clips 9' are secured to the outer ends of the elastic members 8' by enlarging and flattening the inner end of the longer side 21' of the clip, as at 33, and providing this enlarged portion with a transverse opening 34, the outer end of each of the elastic members 8' being passed through the opening 34 of the respective clip and secured to the body portion of the elastic member by stitching, the upper terminal of the elastic member being preferably folded inwardly as shown. The inner side edges of the sides of the clip in this modified form of the invention are beveled as in the first form described.

As shown in Fig. 9, the short elastic members 8'' may have their tabs at the inner ends thereof hooked into an eye 35 of the connecting link 37', a link similar to that illustrated in Figs. 6 to 8, 110 inclusive; or if desired, as shown in Fig. 10, the tabs at the inner ends of the elastic members 8''' may be hooked through the upper slot or opening 30' in the respective connecting link 27' to slide from side to side of the latter.

What is claimed is:

A pair of suspenders having loops at the front ends of the shoulder straps and provided with links connecting the loops with the suspender ends, and a shirt hold-down attachment comprising elastic members consisting of narrow strips of elastic material and extending upwardly from the links and having their lower ends arranged between the sides of the loops of the shoulder straps, tabs located between the sides of the loops and concealed within the same and linked into the said links and secured to the lower ends of the elastic strips, and clips composed of two sides of unequal length and a connecting top portion, the longer side being secured at its lower end to the elastic member and the shorter side curved laterally to form a flaring entrance space to receive the fabric of a shirt, said elastic members being adapted to exert a downward pull on the shirt in two directions, whereby the bosom of the shirt is held in a smooth, flat, unwrinkled condition.
